UNITED STATES PATENT OFFICE.

ALFRED LEANDER RIGGS, OF PITTSBURGH, PENNSYLVANIA, ASSIGNOR TO VISIBLE SPARK PLUG COMPANY, A CORPORATION OF DELAWARE

SPARK-PLUG.

1,296,318.

Specification of Letters Patent.

Patented Mar. 4, 1919.

Application filed January 23, 1917. Serial No. 143,973. Renewed July 31, 1918. Serial No. 247,672.

To all whom it may concern:

Be it known that I, ALFRED L. RIGGS, a citizen of the United States, residing at Pittsburgh, in the county of Allegheny and State of Pennsylvania, have invented new and useful Improvements in Spark-Plugs, of which the following is a specification.

This invention relates to spark plugs. Its object is to provide a spark plug in which provision is made for ascertaining at a glance whether or not the ignition circuit or current is flowing across the gap between the power and ground electrodes, or is being short circuited in any of the usual ways. 15 To this end the invention comprises a spark plug in which a portion of one of the electrodes, preferably the power electrode, is exposed so as to be visible at all times while the engine is in operation, so that a person at a glance can see whether the current is bridging the gap between the electrodes, whereby in a multiple cylinder engine a short circuit or failure of the current to bridge the gap of any particular plug is easily 20 located, rendering it unnecessary to disturb any of the plugs other than the one which is at fault.

A further object of the invention is to provide simple and reliable means for obtaining access to the exposed portion of the power electrode and the terminal associated therewith, said parts forming an auxiliary or pilot gap across which the current must jump before reaching the gap-forming 25 points at the inner end of the plug.

With the above and other objects in view, the invention consists in the novel construction, combination and arrangement of parts hereinafter described and claimed.

40 In the accompanying drawings, Figure 1 is a view partly in side elevation and partly in diametrical section of a spark plug embodying the invention; Fig. 2 is a detail perspective view of the sleeve or cap; Fig. 3 is a similar view of the coupling or clamping band; Fig. 4 is a detail perspective view of another form of sleeve or cap; Fig. 5 is a similar view of the clamping band used in conjunction with the cap illustrated in Fig. 4; Fig. 6 is a detail perspective view of the ring forming the auxiliary spark terminal; Fig. 7 is a fragmentary section similar to the upper portion of Fig. 1 showing modified forms of cap, clamping band and ring

terminal; Fig. 8 is a detail perspective view 55 of the clamping band used in Fig. 7; Fig. 9 is a fragmentary sectional view similar to Fig. 7 showing another modification in the sleeve or cap; and Fig. 10 is a similar view showing a modification in the form of the 60 ring terminal.

The present invention is an improvement on the spark plug shown in my Patent No. 1,241,012, issued Nov. 20, 1917.

The plug, as illustrated in Fig. 1, comprises the usual metal body or shell 1 having the reduced and threaded portion 2 by which the plug is screwed into a threaded hole in the engine cylinder, the clamping nut 3 which serves to tightly secure in the 70 body or shell 1, the insulating core 4 of porcelain or raw hide and which is provided with the central power electrode 5, and a plurality of ground electrodes 6 which protrude from the body or shell 1. 75

In carrying out this invention the end portion of the insulating core 4, beyond the shell 1 and the clamping nut 3, is formed with an annular recess or groove 7, and surrounding the end portion of the core 4 is a 80 metal ferrule, sleeve or cap 8 which is of cylindrical form and provided at diametrically opposite points with outwardly projecting lips, tenons or projections 9. Surrounding the inner end of the sleeve 8 is a 85 clamping or coupling band 10 of circular split form, and provided adjacent to the split therein with outwardly extending perforated ears 11 through which is inserted a clamping bolt or screw 12, by means of 90 which the band 10 is firmly clamped around the cap 8. The band 10 is provided at suitable points with slots or elongated openings 13 to receive the projections or lips 9 of the cap 8, and is further provided along the inner or bottom edge thereof with inwardly extending lips or projections 14 adapted to enter the groove or annular recess 7 in the core 4, so that said band 10 serves to firmly 95 secure the cap 8 to the exposed end portion 100 of the core.

Within the cap 8 and resting against the end of the core 4 is a spark terminal in the form of a feed ring 15, the inner wall or bore of which is in the shape of an hour 105 glass, that is, formed with reversely beveled surfaces 16 and 17 forming an annular edge or vertex 18, which encircles the exposed

extremity of the electrode 5 as shown in Fig. 1. Arranged beyond the ring 15 is a transparent panel 19, usually of glass, which is confined between packing rings 20 and 21 of some soft material which will prevent fracture of the glass panel 19. The outer end of the cap 8 is deflected or spun inwardly to form an annular retaining flange 22 substantially semicircular in cross section.

The feed ring 15, illustrated in detail in Fig. 6, is split or divided diagonally as indicated at 25 so that it is rendered self expanding in order to maintain a tight electrical contact with the inner wall of the cap 8.

The feed wire (not shown) of the circuit may be connected to the clamping band 10 by means of the bolt or screw 12 or in any other way desired. By reason of the fact that the band 10, the cap 8 and the ring 15 are of metal or conducting material, the current is conducted to the ring 15 and jumps therefrom to the exposed end of the electrode 5, then passes through the length of said electrode and jumps to the ground electrode 6 and is grounded in the usual way to the body of the engine.

Instead of forming the cap 8 and the clamping band 10 in the manner hereinabove described, they may be formed as shown in Figs. 4 and 5, in which the cap 8^a is shown as formed at diametrically opposite points with slots or circumferentially elongated holes 23, while the clamping band 10^a is formed along the inner edge thereof with inwardly extending lips or projections 24 which are insertable through the holes 23 and are of sufficient length to also enter the annular recess or groove 7 in the insulating core 4. The result in both cases is the same, the clamping ring 10^a serving to securely fasten the cap 8^a on the core.

Another arrangement of interlocking means between the clamping band and the cap is illustrated in Figs. 7 and 8, in which the cap 8^b is shown as corrugated or formed with threads 26, while the clamping band 10^b is correspondingly threaded or corrugated, as shown at 27, to engage and interlock with the threads or corrugations 26, and is also provided adjacent to its inner or lower edge with inwardly extending lips or projections 28 which enter the groove or annular recess 7 of the core 4. In Fig. 7 the terminal ring, indicated at 15', is shown as pressed out of sheet metal and substantially V-shaped in cross section. Its function and operation, however, is identical with that of the ring 15 of Fig. 1.

Another form of feed ring is shown in Fig. 10, the same being spun or pressed out of sheet metal to comprise a hollow cylindrical body or wall 30, a recurved annular

portion 31, and a circular flange 32, the opening in which is of greater diameter than the external diameter of the electrode 5 so that the current may jump from the ring to said electrode at any point around the electrode.

In lieu of a ring terminal as hereinabove described, an L-shaped spark terminal 29 may be brazed or otherwise fastened to the inner surface of the cap 8^c, as shown in Fig. 9, the extremity of said terminal being located at such distance from the adjacent exposed extremity of the electrode 5 as to provide for the necessary gap across which the spark must jump.

Under any of the forms hereinabove described and illustrated in the drawings, the current, in order to reach the electrode 5, must jump across the gap between the terminal and the electrode 5. The chamber in which this spark takes place is inclosed and protected by the transparent panel hereinabove described which is located directly in the end of the spark plug. The attendant may thus observe at a glance whether or not the current is reaching the electrode 5 and therefore reaching the sparking points formed by the power and ground electrodes at the inner end of the plug. This is especially valuable in multiple cylinder engines, as the attendant may quickly ascertain which plug or plugs are failing to perform their function. The arrangement described also operates to intensify the spark delivered within the combustion chamber of the cylinder by reason of the fact that the current is forced to bridge two gaps instead of the usual single gap. By loosening or removing the clamping member 12, the clamping band and the cap 8 may be quickly detached so as to give access to the ring terminal and the adjacent end of the power electrode for cleaning or repair purposes.

The cap or sleeve 8 with the contained and attached elements forms an attachment which can be applied to any type of spark plug having an insulating core with an axial electrode, and in case of breakage of the core said attachment can be removed and applied to a new plug. The auxiliary or pilot spark gap is entirely inclosed so that it cannot short-circuit and be rendered inoperative by the entrance of moisture or dirt. The upper surface of the glass 18 is exposed and readily accessible for cleaning so that the spark is at all times visible.

The attachment is very compact and projects above the top of the insulating core only a short distance, and therefore avoids unnecessary projecting parts which would be liable to injury when working around the engine, or which would be broken in case the plug is accidentally dropped.

I claim:

1. In a spark plug, a split feed ring with

beveled extremities encircling one of the electrodes and forming an annular gap space surrounding said electrode, a current conducting cap serving to hold said feed ring in fixed relation to said electrode, and means for anchoring said cap to the core of the plug, said means consisting of a clamping band encircling said cap and having a separable and interlocked connection there-
10 with.

2. In a spark plug, a feed ring encircling one of the electrodes and forming an annular gap space surrounding said electrode, a current conducting cap serving to hold said feed ring in fixed relation to said electrode, and means for anchoring said cap to the core of the plug, said means consisting of a clamping band encircling said cap, said cap and band having one a projection and the 15 other an opening to receive said projection, to prevent movement of the band and cap.

3. In a spark plug, in combination with an insulating core and an electrode extending therethrough and projecting beyond the end 20 thereof, of an auxiliary spark attachment comprising a metal sleeve or ferrule fitting over the end of said core and open at its outer end, a spark terminal in said sleeve or ferrule in conducting relation thereto and 25 in sparking relation to the end of said electrode, a transparent member in said sleeve or ferrule outside of said spark terminal and closing the open end of said sleeve or ferrule, and means for securing said sleeve or 30 ferrule to said core, said means consisting of a clamping ring encircling said sleeve or ferrule and having a separable and interlocking connection therewith and having means to engage said core.

4. In a spark plug, in combination with an insulating core and an electrode extending therethrough and projecting beyond the end thereof, of an auxiliary spark attachment comprising a metal sleeve or ferrule fitting 40 over the end of said core and open at its outer end, a spark terminal in said sleeve or ferrule in conducting relation thereto and in sparking relation to the end of said electrode, a transparent member in said sleeve or ferrule outside of said spark terminal and closing the open end of said sleeve or ferrule, and means for securing said sleeve or ferrule to said core, said means consisting of a split clamping ring surrounding said 45 sleeve or ferrule and provided with means for engaging said core, said sleeve and ring having one a projection and the other an opening to receive said projection.

opening to receive said projection to interlock the same.

5. In a spark plug, in combination with an insulating core provided near its outer end with a recess, and an electrode extending through said core and projecting beyond the end thereof, of an auxiliary spark attachment comprising a metal sleeve or ferrule fitting over the end of said core and open at its outer end, a clamping ring surrounding said sleeve or ferrule and provided with inturned portions engaging the recess in the core and serving to secure the 50 sleeve or ferrule to the core, a spark terminal in said sleeve in conducting relation thereto and in sparking relation to the end of said electrode, and a transparent member in said sleeve outside of said spark terminal 55 and closing the open end of said sleeve.

6. In a spark plug, in combination with an insulating core provided near its outer end with a recess, and an electrode extending through said core and projecting beyond the end thereof, of an auxiliary spark attachment comprising a metal sleeve or ferrule fitting over the end of said core and open at its outer end, a spark terminal in said sleeve in conducting relation thereto and 60 in sparking relation to the end of said electrode, a transparent member in said sleeve outside of said spark terminal and closing the open end of said sleeve, and a split clamping ring surrounding said sleeve or ferrule and having interlocking engagement therewith and provided with means entering the recess in the core and serving to secure the sleeve to the core.

7. In a spark plug, in combination with an insulating core provided near its outer end with a recess and an electrode extending through said core and projecting beyond the end thereof, of an auxiliary spark attachment comprising a metal sleeve or ferrule fitting over the end of said core and open at its outer end, a spark terminal in said sleeve in conducting relation thereto and in sparking relation to the end of said electrode, a transparent member in said sleeve outside of said spark terminal and closing the open end of said sleeve, and a split clamping ring surrounding said sleeve or ferrule and provided with means entering the recess in the core, said sleeve and ring 100 having one a projection and the other an opening to receive said projection.

In testimony whereof I affix my signature.
ALFRED LEANDER RIGGS.
